UNITED STATES PATENT OFFICE.

WILLIAM H. BARTH, OF NEW YORK, N. Y., ASSIGNOR TO THE HENRY McSHANE MANUFACTURING COMPANY, OF BALTIMORE, MARYLAND.

DESIGN FOR A HINGE.

SPECIFICATION forming part of Design No. 24,323, dated May 21, 1895.

Application filed January 9, 1895. Serial No. 534,383. Term of patent 7 years.

To all whom it may concern:

Be it known that I, WILLIAM H. BARTH, a citizen of the United States, and a resident of New York, in the county of New York and State of New York, have invented and produced a new and original Design for a Hinge for Water-Closet Seats and Covers, of which the following is a specification.

My design is illustrated in isometrical projection in the accompanying drawing, to which reference is made, and is characterized by the following peculiarities:

The upper or top leaf A is composed of two arms or parts which are carried upward and forward and gradually approach each other at their outer or free ends where they merge into the trefoil portion or extremity a; while the arms constituting the two lower leaves B B, are independent of each other and are constructed of a general plate or bar form with a trefoil formation, b, at the outer extremity of each.

The securing stands C, are of a general

truncated conical form, having a stud like portion, c, depending from their lower ends, 2; while the upper end of each is provided with a ball-like head, c'.

The pin or pintle D, is made as a round bar or rod, and is provided at each of its ends with an enlarged polygonally shaped head, 3; d, which terminates at its extremity in a ball shaped ornament, d'.

The several parts being of the contour thus described, form, when united, a highly ornamental hinge which is at once attractive and 35 unique in design.

I claim—

The design for a hinge for water closet seats and covers, substantially as shown and described.

In testimony whereof I have hereunto set my hand this 5th day of January, A. D. 1895.

WILLIAM H. BARTH.
